TRANSPORTATION OF LIQUEFIED NATURAL GAS
Percival C. Keith, Peapack, N.J., assignor to Hydro-
carbon Research, Inc., New York, N.Y., a corporation
of New Jersey

Filed Aug. 22, 1961, Ser. No. 133,197

3 Claims. (Cl. 62—45)

This invention relates to the transportation of liquefied natural gas and similar normally gaseous materials which must be maintained at temperature levels below about -40° F. to permit handling at substantially atmospheric pressure. It particularly relates to improvements concerning ship storage whereby the liquefied material may be transported by water carrier.

The liquefaction and storage of natural gas at about -260° F. has been suggested as economical for supplying gas in industrial areas where fluctuating gas demands often exceed the capacity of available facilities. Where, however, the available gas is at remote geographic areas and shipment must be by water borne carrier, many new problems have arisen. Not only is ship transportation relatively slow, thus causing long periods of heat infiltration which tends to vaporize a substantial part of the cargo, but also a ship has substantial turbulence which, in itself, further tends to vaporize the liquid. In a ship, these vapors are an especially serious hazard for they are explosive when mixed with air.

My invention relates primarily to the handling of liquefied natural gas and to the control of vaporization of the liquid but as hereinafter pointed out, it is also applicable to the handling of other liquefied gases such as propane, oxygen or nitrogen which are subject to liquefaction at temperatures in the range of -40° F. to as low as -424° F. and thus subject to objectionable vaporization resulting from ambient heat infiltration.

A principal object of my invention is to provide a simplified liquid storage unit for liquefied gases which unit is suitable for assembly in a ship's hold and in which structural stability is combined with safety against hazardous gases to the end that liquids may be readily stored and discharged.

The invention further contemplates storing of the liquefied gases in the sub-cooled state so that under the normal storage or shipping conditions (considering time, temperature, and rate of heat infiltration), vaporization of the in-transit liquid will be substantially avoided. As the stored liquids in such condition exert a vapor pressure which is less than one atmosphere absolute, the liquid is blanketed with a gas having relatively low solubility in the stored liquid and a boiling point below the temperature of the stored liquid so that effective pressures can be developed to prevent flow of atmospheric gases into the liquid storage space.

As a specific feature of the invention, it is proposed to sub-cool liquefied natural gas to a temperature of about 10° F. below the bubble point so that a container of liquid when shipped overseas during a customary period will only be heated to a bubble point which is approximately -260° F. thus avoiding the production of any hazardous vapors and making it possible to dispense with a re-liquefaction equipment on board the carrier.

Further objects and advantages of the invention will appear from the following description of a preferred form of embodiment thereof when taken with the attached drawing illustrative thereof and in which:

2

FIG. 1 is a schematic central transverse vertical section taken through a marine vessel.

FIG. 2 is a horizontal cross-section taken substantially on the line 2—2 of FIG. 1.

5 As shown in FIG. 1, the vessel 10 which is represented as a marine vessel such as a ship or barge, but which might also be a land vehicle body, is shown to have a supporting bottom 12, sides 14 and a top deck or flooring 16. While the vessel as shown includes at least a hold 10 encompassed by these walls and the customary bulkheads and extends the full depth below decks, it will be understood that the vessel might be of a multiple deck type and the unit shown might be a typical insulated hold.

Within the defined hold I provide one or more liquid cargo containers or tanks 20 which are preferably made of aluminum. While these tanks may be of a suitable shape, I prefer to use a series of cylindrical tanks in contact one with another as shown in FIG. 2 and conveniently welded to each other as by means of the stays 22, 20 to become a rigid one piece nest. This assures a common movement of all tanks about a central point and thus does not interfere with expansion or contraction.

The tanks 20, if cylindrical, are provided with dished or hemispherical top and bottom portions with bottom skirt portions 26 which rest on and are permanently affixed as by welds, not shown, to an aluminum floor plate 28. This plate, in turn, is provided with a knob 30 which extends into a suitable cooperating slot in the flooring 32. This flooring which is usually of oak planking is suitably mounted on insulation such as balsa wood generally shown at 36 carried on the bottom 12 of the hull.

On the side walls of the hold, including the bulkheads, I prefer to use one or more layers of semi-permanent or bonded insulation 36a which consists of foam glass or cork or other pre-shaped insulation. This layer is mounted in permanent array as by the use of suitable binders which hold it against the hull wall. With its cellular structure, gas circulation within the insulation is substantially zero and cold spots on the hull wall are thereby prevented. Such insulation proves to be most effective in reducing heat infiltration down to about -200° F.

I also prefer to line this fixed insulation with one or more rows of a semi-fixed granular or fibrous secondary insulation 36b which may be of rockwool packed in bags of a suitable dimension. The bags themselves are preferably of impervious material and thus serve to decrease gas currents. Such secondary insulation is appropriately held in place to leave a space 37 between the wall insulation and the tanks which space can be used for an access space to permit an inspection or repair of the outside of the tanks 20. Such a space also becomes an important insulator of the very cold surfaces of the tanks 20. A further space, designated 40 in FIG. 2, between adjacent cylindrical tanks is also large enough for inspection and repair. With rectangular tanks, this internal space is unnecessary.

The hold is completed by an insulated cover 42 which is supported by skirts 43 on the upper portions of the tanks 20. The cover includes an aluminum plate 44 covered as by the use of cork or rockwool insulation 45. A carbon steel plate shown at 46 is laid on this insulation and forms a crawl space 52 below deck 16. The insulated cover is flexibly sealed at 48 to the insulated wall of the hold.

In accordance with my invention, I propose to fill the

tanks 20 in a hold through a fill header 60 with a normally liquefied gaseous material such as natural gas. This header 60 is connected through line 62 to the bottom of one of the tanks of the nest and by the intermediate transfer lines 64 it is possible to fill all of the remaining tanks in the nest. The last tank in the series is provided with a discharge line 65 which discharges into surge tank 66. When the liquid in the surge tank reaches the desired level, all of the tanks in the particular nest are full.

During in-transit periods, I find it desirable to maintain a circulation of liquid through the tanks to prevent any substantial temperature differences. This is accomplished by the use of pump 70 which takes suction by line 68 from the surge tank 66 and through discharge line 72 and fill line 62 can continuously circulate the liquid through the tanks and back through outlet line 65 to the surge tank. Normally, a turnover of liquid on a daily basis assures uniform temperature of the liquid.

Discharge of the liquid from the tanks is preferably by the use of a high pressure gas source such as an inert gas, for example, nitrogen or the same type of gas in storage, for example, natural gas. This may be connected through gas header 74 through gas line 76 to the top of the surge tank 66. This will impose a head on the liquid in surge tank 66 which in turn will force the liquid out through line 65 into the last tank of the nest thence through fill line 62 to liquid header 60.

During the return trip of a ship such as described, it has been found desirable to provide for a recirculation of low temperature gases such as methane or nitrogen or mixtures thereof to assure a uniform low temperature of the tanks. This is accomplished by the use of blower 82 which takes suction from the upper part of surge tank 66 through line 80 and then discharges through line 82 and cooler 84 into header 60. By the same piping 62, tanks 20, and piping 65, the gases flow back to the surge tank 66. The cooler 84 may be nitrogen cooled.

Ordinarily provision is made for possible expansion of the liquid in the cargo tanks 20. As the liquid expands into surge tank 66 through line 65, the excess may be drawn off through pipe 88 to the expansion tank 21. Possible vapors can be vented through line 90 back to the surge tank 66.

The transportation or storage of a normally liquefied gas at about its bubble point is usually accomplished at atmospheric pressure notwithstanding the constant vaporization of gas due to heat infiltration. In such a unit, especially with an inflammable gas, there is always a gas discharge which must be burned as fuel or reliquefied. If, however, gas is stored under sub-cooled liquid conditions, the vapor pressure is of a low absolute value and negative referred to atmospheric conditions. Any leakage of air from the atmosphere into a tank of liquid methane, for example, would thus tend to become extremely hazardous.

I find that I can benefit by the sub-cooling technique and avoid all of the gas flares or extra refrigeration equipment that has been used heretofore to reduce the danger, or loss, or both, resulting from heat infiltration to liquefied gases in ship or land storage.

This is accomplished, as shown in FIG. 1, by utilizing a lower boiling gas such as nitrogen in header 74 which enters surge tank 66 through line 76 above the liquid level. In addition, I float on the liquid a substantially impervious sheet 92 made of a suitable material such as aluminum which nearly covers the exposed liquid. While there is a freedom of movement of this plate 92 with the rise and fall of the liquid level, the size of the sheet is such that the actual contact of the nitrogen above the sheet with the exposed area of the liquid is very small. The rate of occlusion of the gas in the liquid is thus also very small and not objectionable.

There is the further advantage that this gas tends to work on all of the liquid in all of the tanks, in all of

the holds, again with the advantage that the actual surface exposed to the gas is extremely small when the total horizontal surface is considered.

As a result, I find that the solubility of nitrogen in the liquid methane does not present a technical problem, and, in fact, on revaporization as soon as the methane is heated to be vaporized for use, the nitrogen is driven off. It is thus possible to maintain the liquid methane at a temperature condition under which it exerts a vapor pressure less than one atmosphere absolute with in fact having a vacuum present in the chamber.

The degree of sub-cooling can be adjusted to the desired extent but normally a ship voyage of a week would tend to boil off about 1.5% of the contents of the tanks resulting from about a 4° F. temperature rise. I prefer, under such conditions, to sub-cool the methane to about -270° F. which is about 12° F. below the bubbling temperature. This can be accomplished by a final stage of liquefaction which can be by heat exchange with liquid nitrogen.

My invention is particularly advantageous for ocean going shipment due to the long period involved and the advantage of eliminating expensive re-refrigeration equipment. It is also possible, however, to benefit from my invention in connection with stationary storage vessels where sub-cooling can be accomplished with less energy consumption than the re-liquefaction can be accomplished.

The pressurizing of the nest of tanks 20 not only to discharge liquid but for other purposes, can be accomplished by the use of reenforced tanks and connections. In accordance with the invention, however, I provide only a secondary containment generally shown as a clad shield or cover element 45. This is necessary only on the outside tanks of the nest and may be a series of welded plates.

Preferably I use a series of weld pads or plates 46 attached in the shop to the tanks. These weld pads serve not only to attach the clad cover element 45 but also the external filler plate or web 47. As the pads 46 are shop affixed, the remaining welding of the cover element 45 and filler plate 47 can be accomplished in the field without in any way weakening the tank structure.

It will be apparent from the foregoing disclosure that modifications may be made to my invention and I thus desire a broad interpretation of my invention within the scope and spirit of the disclosure herein and of the claims appended hereinafter.

I claim:

1. In the method for the safe storage of a highly volatile, low boiling, liquefied, combustible gas in large volumes at temperatures below the boiling point wherein the gas is liquefied under substantially atmospheric conditions, the further steps of sub-cooling the liquid to a temperature substantially below the boiling point wherein the vapor pressure condition is less than one atmosphere absolute, confining the liquid in an insulated storage container, interconnecting the storage container with a tank of relatively small horizontal surface, applying an inert and relatively low solubility gas to the small horizontal surface whereby the inert gas goes into partial solution in the liquid to thereby maintain a partial pressure substantially atmospheric and thereby prevent inflow of air from the surrounding atmosphere and avoid the formation of a combustible mixture with the liquefied gas.

2. The method of storage of a combustible gas as claimed in claim 1 wherein the combustible gas is substantially liquid methane, the sub-cooling is to a temperature in the order of -270° F. and the blanketing gas is nitrogen.

3. The method of storage of a combustible gas as claimed in claim 2 including the further step of covering a major part of the exposed surface of the liquid methane with a substantially gas impervious surface to re-

duce the area of the liquid surface subject to gaseous occlusion.
